PRESSURE OPERATED MAGAZINE PENCIL

Heinrich Morlock, Pforzheim, Germany

Application August 29, 1939, Serial No. 292,463
In Germany September 23, 1938

3 Claims. (Cl. 120—17)

Pressure operated magazine pencils with two gripping elements arranged one behind the other are known, in which a connecting tube enclosing the rear gripping element is connected with the front gripping element by two longitudinal tongues formed on the front edge of the connecting tube, which tongues have bent front ends which are hooked into the tubular rear end of the front gripping element which has an annular bead open in inward direction and in which the outwardly bent front ends of the longitudinal tongues of the connecting tube engage.

In this manner a movable connection of the front ends of the longitudinal tongues with the rear ends of the front gripping element is attained, this mutual movability is, however, not sufficient in cases where irregularities in the lead diameter occur, to regulate the return movement of the front gripping element so that it reliably closes after the rear gripping element. If it closes prior thereto, in addition to other disadvantages, it is not possible to enable one and the same exceptionally long lead to be gripped by both elements at the same time.

This objection does not, however, occur if the front end of the longitudinal tongues, according to the invention, can be shifted freely in the annular bead to such an extent that the front gripping element always closes after the rear gripping element.

To ensure the free displacement of the outwardly bent front ends of the longitudinal tongues within the annular bead and not to impede the freedom of movement by the outwardly directed ends bearing against the inner wall of the bead, a braking device is preferably arranged in the point of the pencil, which device acts on a thickened portion of the tube of the front gripping element, for example, by means of resilient arms, so that this element only participates in the longitudinal displacement of the connecting tube which surrounds the rear gripping element when the thickened portion of the tube is located outside the range of the braking device, or when the ends of the longitudinal tongues on the front or rear end bear against the bead.

An embodiment of the invention is illustrated by way of example in the four figures of the accompanying drawing, in which—

Fig. 1 shows the magazine pencil in longitudinal section,

Figs. 2, 3 and 4 show the front end of the magazine pencil in longitudinal section, and each shows the gripping element in a different position.

The pressure operated magazine pencil comprises a tubular front gripping element 1 and a rear tubular gripping element 17. These elements are arranged in a tube 10 whose rear end is rigidly connected to a lead magazine tube 11 and pressed in rearward direction by a pressure spring 23. The tube 10 has two longitudinal slots 16 through which two outwardly bent flaps 32 on the rear edge of the rear gripping element 17 project and serve for guiding this element. A pressure spring 34 acts on these flaps 32 through the intermediary of a sleeve 33. The tube 10 has also on its front end two longitudinal tongues 9 displaced through an angle of 90° relative to the longitudinal slots 16, the front ends 8 of these tongues 9 being bent outwardly. These front ends 8 engage from the inner side in an annular bead 50 formed on a tube section 5 and open in inward direction, this tube section 5 having a narrowed front end fitting tightly on the rear end of the front gripping element 1. In this manner the front gripping element 1 is connected with the lead magazine tube 11.

The above mentioned internal parts are enclosed in a casing comprising three screw-connected sleeves 21, 25 and 36 and a screwed-in point 38. The sleeve 25 has an inturned bottom flange with two radial slots 28 through which the two longitudinal tongues 9 of the tube 10 extend. On the inner edge of the flange a tube section 29 is fixed, whose rounded inner front edge 30 acts as clamping ring on the tapered outer surfaces of the clamping jaws 18 of the gripping element 17. A metal casing sleeve 41 surrounding the whole rear part of the magazine pencil has a portion clamped between the sleeve 36 and the point 38.

The annular bead 50 is of cylindrical shape and has in its interior so much clearance for the front ends 8 of the longitudinal tongues 9, that these can freely shift longitudinally therein. Consequently, the front gripping element 1 does not move along the entire path of movement of the lead magazine tube 11, the connecting tube 10 and the longitudinal tongues 8. The path of movement of the front gripping element 1 can be shorter than the displacement of the longitudinal tongues 9 by the distance which these tongues can shift freely in the bead 50. Thus, the front gripping element 1 will no longer project from the aperture in the front a distance equal to the path of movement of the longitudinal tongues 9. The clamping cone on the front gripping element 1 is shorter so that, taking into consideration all possible inaccuracies

regarding the thickness of the leads, the closing of the front gripping element 1 only takes place when the rear gripping element 17 is closed. A lead, which is gripped by both elements 1 and 17 at the same time, can then be inserted without danger of fracture.

To prevent the front gripping element 1, during the forward movement of the longitudinal tongues 9, from carrying out a forward shifting movement of the same length owing to the friction between the longitudinal tongues 9 and the rear portion of the tube 5, a braking device 58 is arranged in the point 38 of the pencil and resiliently bears against the tube of the front gripping element 1 with at least two oppositely situated arms 54. The effect of this braking device is assisted by a thickening 55 on the element 1.

During the displacement of the longitudinal tongues 9 the gripping element 1 will first be carried along by the above mentioned friction until a shoulder 56 on the thickening 55 contacts with the brake jaws 57 (Fig. 2). In this position the clamping cone of the front gripping element 1 is already out of the range of the opening of the point. The front ends 8 of the longitudinal tongues 9 slide forward within the bead 50 during the continued movement of these tongues owing to the resistance which the shoulder 56 encounters on the brake jaws 57. During this period the front gripping element 1 does not continue its forward displacement. Only when the front ends 8 bear against the front wall of the bead 50, does the front gripping element 1 continue its forward movement. This element allows the lead, which in the meantime is pushed forward by the jaws 18 of the rear gripping element 17, to slip partly through it and also moves partly with the lead the above mentioned distance in forward direction, the thickening 55 engaging between the brake jaws

57 (Fig. 3). These latter now hold the front gripping element 1 in advanced position until the jaws 18 of the rear gripping element are once more in gripping position (Fig. 4). Shortly after this moment the front ends 8 again bear 5 against the rear end of the bead 50 whereupon the front gripping element 1, after the jaws 18 of the rear gripping element have assumed their gripping position, will also be pulled back into this position, the thickening 55 again leaving 10 the range of the brake jaws 57 (Fig. 1).

I claim:

1. In a pressure operated magazine pencil the combination of two gripping elements arranged one behind the other, a tube enclosing the rear element, two longitudinal tongues on said tube and connecting said tube to the front gripping element, a bead formed on the rear end of said front element and open in inward direction, and outwardly bent front ends one on each of 20 said tongues and shiftably engaging in said bead to allow said front gripping element to close after said rear gripping element.

2. In a pressure operated magazine pencil as specified in claim 1, a braking device for the 25 front gripping element adapted to hold said front element in advanced position until the rear gripping element is closed.

3. In a pressure operated magazine pencil as specified in claim 1, a braking device comprising 30 a tube surrounding the front gripping element, resilient arms extending forwards from said tube, brake jaws one on the front end of each of said 35 resilient arms, and a thickened portion on said front element adapted to engage between said jaws to arrest the forward movement of said front element until the bent ends of the resilient tongues contact with the front end of the bead.
